PROCESS AND APPARATUS FOR CONVERTING LIQUID SUBSTANCES INTO THE FORM OF GRANULES

Nicolai Stephansen, Oslo, Norway, assignor to
 Norsk Hydro-Elektrisk Kvaestofaktieselskab,
 Oslo, Norway

Application June 10, 1933, Serial No. 675,187
 In Norway October 17, 1932

3 Claims. (Cl. 159—3)

My invention relates to a process and an apparatus for the treatment of liquid substances as melts, solutions, emulsions or pulpy masses for the purpose of solidifying the same and converting them into the form of granules.

Among the various kinds of apparatus used for converting liquid substances into the form of granules, rotating discs have been employed with or without combination with heating means. 10 By conducting the substances down on to a quickly rotating disc in the near vicinity of its centre, the substance is flung outwards, the water evaporated and the mass converted into a more or less pulverized form, all according to the speed of rotation of the disc and the viscosity, quantity etc. of the substance. For instance, by this method milk can be concentrated to a powder (dry milk) or concentrated salt solutions can be converted into solid substances, say nitrate of lime or other materials. 15

When this method is to be used for producing fertilizers in granular form, the problem arises to devise large plants and apparatus capable of handling hundreds of thousands of tons per annum. It is then either necessary to make use of a great number of separate machines, or to mount several discs on one axle. As each of the discs must have its separate supply of solutions or melted salt, the apparatus becomes very complicated and is sensitive in operation. 20

The present invention relates to a process for the production of a granular product from liquid substance whereby it is possible in one and the same apparatus to obtain a manifold increase in the yield. The invention also aims at constructing a suitable apparatus for carrying out the process. 25

Experiments show that if, without further treatment, liquid substances in the form for instance of a pulpy mass are spread over a rotating disc, so that the substance thereby gradually becomes converted into a very thin layer, the centrifugal force (rapidly increasing with the distance from the centre of the disc) will cause 30 the layer or film formed to be broken up and so the mass becomes caked before it leaves the disc. The aim of the present invention is to prevent this. For this purpose I cause the film or flowing mass to be divided into two separate parts 35 at a suitable distance from the centre of the disc, it being as shall hereafter be more precisely described, thereby possible to reduce the distance through which the layer must pass before it leaves the apparatus, while at the same time 40 obtaining a layer of the necessary thinness.

More specifically described the process consists in dividing the film or flowing mass at a suitable distance from the centre of the disc into rays, so that outside of this point the mass is directed in two separate parts to another rotating part of the machine. These rays spread over the rotating surfaces forming, before the mass leaves the disc, two separate films of a thickness corresponding to the peripheral speed which is suitable for the formation of an even product. 5

The process as above indicated will be fully understood by the description below the two forms of apparatus for carrying out the process.

Fig. 1 is a diagrammatic axial section of the simplest form of apparatus.

Fig. 2 a similar drawing of a more complete apparatus.

Fig. 3 is a perspective view of a part of Fig. 1 on an enlarged scale, illustrating the manner in which the film of liquid material is divided in two sets of rays and thereupon led to form two separate films. 20

Figure 4 is a sectional view of the apparatus shown in Figure 1 showing the means for heating the working surfaces. 25

In Fig. 1, A represents a driving shaft on which is fixed a central disc B, shaped like a plate. Surrounding this is a larger disc C, which in cross section has the shape of two cones united by a rounded portion as shown on the drawing and 30 rotating with the central disc. On this outer disc blades or shovels E, which alternatively lead to the upper and the lower part, are formed pointing towards the plate or disc B (see also Fig. 3). The substance which is to be dried and granulated is conducted through pipe D down on the disc B. On account of the centrifugal force, the mass is 35 flung into the blades E on the outer disc and the film is thereby cut into rays (F, Fig. 3), which is alternately conducted on the upper and lower surface of the disc C. These rays will spread on the surfaces of the disc C, and as they are getting thinner, they will unite and form a continuous film before they reach the edge of the disc, which latter they will leave in the form of powder or 40 granules. Fig. 3 is seen from the axis of the apparatus a little distance above the central disc B. G indicates a vertical, circular section of the film just before hitting the blades E. 45

By giving the surfaces of the disc C a more or less conical shape they will render more or less resistance against the action of the centrifugal force and in this manner the apparatus may easily be adapted for the treatment of different substances. 50

Figure 2 shows how the effect can be still further increased by conducting the substances from the central disc on to several parallel discs, both sides of these discs being used. This apparatus 5 has an axle A, to which is fixed a central disc B. To this there is fixed or integrally connected a ring R. Around this ring again there run two discs, C₁ and C₂, corresponding to disc C as shown in Fig. 1. When the substance is conducted 10 through pipe D, it is flung out from disc B to ring R, which is provided with blades as above described, that convey the substance alternately up and down, to the upper or lower discs respectively. When the substance leaves the ring R, the distribution 15 takes place in exactly the same manner as described above with reference to Fig. 1. In other words, the procedure is repeated.

In such an apparatus there is only one supply 20 pipe, which it is very easy to regulate. If the apparatus is used for pulverizing concentrated salt solutions or melted salts or salts mixtures, the apparatus is as usual constructed with a hollow axle and hollow discs, so that it can be heated by warm water, steam or electricity.

25 In Fig. 4 the shaft A is shown hollow and having a central tube a connected at its lower end, with a channel b formed in the disc B and leading through a bridging connection d to the body C which is in this instance formed with a closed 30 hollow space c. On the other side this space is through a channel e connected with the hollow space of the shaft A. The heating medium is introduced through the pipe a and passes through the channel b to the space c and from th's through 35 the channel e back to the shaft, from where it goes to a heater and so kept circulating through the apparatus. The particular means of heating the apparatus, however, forms no part of the invention.

I claim:

1. The process of treating liquid substance such as melts, solutions, emulsions or pulpy masses for the purpose of solidifying the same, which consists in first causing the liquid mass to be spread by the action of centrifugal force to form a continuous film, thereafter dividing the film into a number of rays, exposing said film rays to a successively decreasing resistance against its radial movement, while at the same time the material 10 is continually extended by the action of centrifugal force until the mass is flung off and left to free fall, during which last period of the process the mass is solidified in the form of granules. 5

2. In a centrifugal apparatus, the combination 15 with a central spreading disc and two annular resistance bodies the inner diameter of which is considerably greater than the outside diameter of the spreading disc, said annular resistance bodies being disposed at an axial distance from each 20 other on both sides of the central spreading disc, of an annular body having greater inner diameter than the spreading disc and smaller outer diameter than the inner diameter of the aforesaid annular bodies and being disposed in the space 25 between said bodies so as to act as a distributor of the material from the central spreading disc to the said annular resistance bodies.

3. In a centrifugal apparatus, the combination 30 with a central rotatable spreading disc, of an annular body surrounding the same and taking part in its rotation, said annular body having surfaces which slope axially and radially along the path of movement of the fluid over said body, the axial slope decreasing from the point at which the liquid 35 strikes to the point at which it leaves said body. 35

NICOLAI STEPHANSEN.
